UNITED STATES PATENT OFFICE.

LEWIS J. EISSLER, OF BASCOM, OHIO.

DESIGN FOR A PICTURE OR MIRROR FRAME.

SPECIFICATION forming part of Design No. 17,287, dated May 3, 1887.

Application filed March 29, 1887. Serial No. 232,912. Term of patent 7 years.

To all whom it may concern:

Be it known that I, LEWIS J. EISSLER, of Bascom, in the county of Seneca and State of Ohio, have invented and produced a new and original Design for a Picture or Looking-Glass Frame, of which the following is a full, clear, and exact description.

The leading feature of my design is that of a horseshoe incased or bordered by figures representing farriers' tools.

The drawing shows a view in perspective of my newly-designed picture or looking-glass frame.

The center figure of the design is that of a horseshoe, A, as seen from its under side, with toe-calk b and nail-heads c exposed. Upon one side of the shoe, and exterior to it, is a figure representing a pair of nail-tongs, B, and upon the opposite side of the shoe, and exterior to it, is a figure representing a hammer, C. The frame is further ornamented on its one end, exterior to the toe of the horseshoe figure A, with a figure simulating a farrier's knife, D, and on its opposite end by a figure representing a rasp or file, E, the heel part of the shoe appearing to rest upon the face of the rasp and the handles of the tongs and hammer appearing to cross the face of the same. These several figures B C D E all simulate farrier's tools and form a border to the central figure of a

horseshoe, A, emblematical of the farrier's trade.

I claim—

1. The design for a picture or looking-glass frame herein shown and described, the same consisting of a central figure representing a horseshoe, A, and opposite side figures representing, respectively, a nail-tongs, B, and hammer C.

2. The design for a picture or looking-glass frame herein shown and described, the same consisting of a central figure representing a horseshoe, A, and opposite end figures representing, respectively, a farrier's knife, D, and a rasp or file, E, the heel ends of the horseshoe figure appearing to rest upon the face of the rasp.

3. The design for a picture or looking-glass frame herein shown and described, the whole being emblematical of the farrier's trade, and consisting of a central figure representing a horseshoe, A, opposite side figures simulating, respectively, a hammer, C, and nail-tongs B, and opposite end figures representing a farrier's knife, D, and rasp or file E.

LEWIS J. EISSLER.
